UNITED STATES PATENT OFFICE

RICHARD POTI, OF DORTMUND, GERMANY

IGNITION ROOF FOR TRAVELING GRATE BOILER PLANTS

Application filed October 5, 1926, Serial No. 139,740, and in Germany October 17, 1925.

Furnace chamber roofs for boiler plants are known, wherein a refractory body forming the entire roof is suspended from iron suspending members. Such iron suspending members are not advantageous because when heating the roof they expand differently to the coherent refractory roof body. Moreover, the iron suspending members cannot resist the great heat but are destroyed in a short time. Tests have shown that such destruction also takes place when the suspending members are completely embedded in the roof body.

These drawbacks are obviated by the present invention according to which an ignition arch for traveling grate boiler plants is produced which consists of a coherent refractory body and refractory supporting bricks for the same, which intimately cohere with the body. The use of the refractory supporting bricks instead of iron suspending members for supporting the arch body has the advantage that during the varying temperature in the furnace chamber the supporting bricks expand or contract to the same extent as the arch body. Moreover, the supporting bricks may be subjected to the same temperature as the arch body without burning or suffering any damage.

An embodiment of the invention is shown in the accompanying drawings by way of example, in which:

Figure 1 is a longitudinal section through an arch according to the invention.

Figure 2 is an elevation of a supporting brick.

Figure 3 is a plan view of the brick.

Several main girders 8 are arranged above a furnace chamber A of a boiler plant not shown and auxiliary girders 8a are arranged transversely to the main girders. Supporting bricks 17, 25 are movably suspended on the auxiliary girders. The bricks comprise (Figs. 2 and 3) a shank 17' of a circular or polygonal cross section with a suspension opening 17" and a head 18.

In order to produce the arch according to the invention, the main and auxiliary girders 8 and 8a are laid and the bricks 17 and 25 suspended therefrom. Additional bricks 26

and 27 of a construction similar to the bricks 17 and 25 may be arranged on girders 4 in the manner as indicated in the drawing.

A boarding (not shown) is then provided underneath the heads 18 of the bricks 17 and 25 in such a manner that it bears against the outer faces of the heads. A plastic mass consisting, for instance, of finely ground burnt magnesite ($MgCO_3$) silicate of alkali (water glass) asbestos, dolomite ($CaMgCO_3$) and water is placed and stamped on the boarding and between the supporting bricks. Apertures 2 are simultaneously formed in the mass through which air for cooling may subsequently enter. The composition of the mass is not always the same but depends on the fuel used.

The mass 1 stamped between the bricks becomes intimately combined with the bricks during its drying process so that when dried it forms with the bricks a solid coherent body. The boarding is next removed and the arch thus produced is supported only by the bricks.

In a further constructional form, another head 19 may be provided on the surface of the head 18 of the bricks 17, the said head 19 extending into a layer 3 and holding the same. The layer 3 is made of a mass similar to that described above and is refractory.

It is also possible when producing the body 1 to form therein apertures 20 with projecting corners 21. When applying the layer 3, the said apertures are filled with the latter 35 and also assist in supporting the same.

I claim:—

1. An ignition arch for traveling grate boiler plants comprising in combination main girders arranged above the furnace chamber, auxiliary girders extending transversely of the main girders, supporting bricks including shanks having heads at one end and openings at the opposite end receiving the auxiliary girders whereby the supporting bricks are movably suspended thereon, a coherent body filling the space between the bricks, said body being supported by the heads of the bricks and forming with the lat- 100

ter a body constituting the top of the furnace chamber.

2. An ignition arch for traveling grate boiler plants comprising in combination 5 main girders arranged above the furnace chamber, auxiliary girders extending transversely of the main girders, supporting bricks including shanks having heads at one end and openings at the opposite end receiving the auxiliary girders whereby the supporting bricks are movably suspended thereon, a coherent body filling the space between the bricks, said body being supported by the heads of the bricks and forming 15 with the latter a body constituting the top of the furnace chamber, said body having cavities therein to increase the heat radiating surface thereof.

In testimony whereof I affix my signature.

20 RICHARD POTH.
